UNITED STATES PATENT OFFICE

2,506,690

INCANDESCENT VAPOR TUBE STOVE

John I. Stein, Muncie, Ind.

Application June 17, 1947, Serial No. 755,031

2 Claims. (Cl. 219—19)

1
This invention relates to heating stoves and more particularly to an electrical heating stove employing incandescent vapor tubes as the source of heat.

A main object of the invention is to provide a novel and improved heating unit employing incandescent vapor tubes as the heat source, said unit being very simple in construction, efficient in operation and compact in size.

A further object of the invention is to provide an improved heating unit which is inexpensive to manufacture, easy to maintain in operation and light in weight.

Further objects and advantages of the invention will become apparent from the following description and claims, and from the accompanying drawings, wherein:

Figure 1 is an elevational view of a heating unit constructed in accordance with the present invention.

Figure 2 is a vertical cross-sectional view taken through the heating unit of Figure 1.

Figure 3 is a detail top plan view of the top conductor ring employed as a contact terminal element for the vapor tubes employed in the heating unit of Figure 1.

Figure 4 is a fragmentary enlarged longitudinal cross-sectional view taken through one of the vapor tubes employed in the heating unit of Figure 1.

Figure 5 is an elevational view partly in cross-section of a modified vapor tube heating unit constructed in accordance with the present invention.

Figure 6 is a horizontal cross-sectional detail view taken on line 6—6 of Figure 5.

Figure 7 is a top plan view of the heating unit of Figure 5.

Figure 8 is an elevational detail view of the terminal bars employed to connect the ends of the vapor tubes of the heating unit of Figure 5 to a source of current.

Referring to the drawings, 11 designates a generally cylindrical housing having an open top and provided with supporting legs 12 and a base plate 13, said base plate being made of refractory electrically non-conducting material, such as tile, fire clay, or the like. The cylindrical housing 11 is made of sheet metal or the like and is provided with a hinged door 14 which provides access to the interior of the housing. The wall of the housing and the door 14 are formed with perforations 15 to allow air to circulate freely through the interior of the housing.

Secured to base plate 13 is a bottom support

disc 16 of suitable refractory electrically non-conductive material, and secured to and supported on upstanding post members 17 rising from bottom disc 16 is a top disc 18 made of the same type of material as bottom disc 16. Secured to bottom disc 16 is an annular ring 19 made of conductive temperature-resistant metal, such as stainless steel or the like and secured to the bottom surface of top disc 18 is a similar annular ring 20. Formed in each of rings 19 and 20 are a like number of uniformly spaced openings 21, the openings of ring 19 being substantially vertically opposed with respect to the openings of ring 20, although ring 20 is somewhat larger in diameter than ring 19 and the openings of ring 20 are on a larger radius with respect to the common vertical axis of the rings than the openings of ring 19. Secured in each set of opposed openings in the respective rings 19 and 20 is a vapor tube 22 having end terminals 23 and 24 received in the opposed openings. Secured to the top ring 20 is a terminal bracket 25 carrying a binding post 26 to which is connected one of the line wires 27 of the current source. The other line wire 28 is connected to the bottom ring 19 and extends thereto through the insulating base disc 16.

Each of the vapor tubes 22 comprises the end terminals 23 and 24 to which are secured an inner shell 29, an intermediate shell 30 spaced outwardly from said inner shell and an outer shell 31 spaced outwardly from the intermediate shell 30. The shells 29, 30 and 31 are made of thin refractory insulating material such as fire clay or the like. The inner tube 29 is filled with a mass of heat insulating material 32 such as rock wool or the like. The spaces between inner tube 29 and intermediate tube 30 and between said intermediate tube and outer tube 31 are filled with conductive gas such as neon, argon or nitrogen or conductive vapor such as tellurium vapor, mercury vapor, or a mixture of conductive gases and vapors.

When the line wires 27 and 28 are connected to a suitable source of current, the vapor tubes 22 will be energized in parallel and the gases or vapors contained therein will become incandescent by the passage of current between the terminals 23 and 24 of the tubes. Said incandescent gases will be at a substantial temperature and will generate appreciable quantities of radiant energy. This radiant energy will elevate the temperature of air circulating through the housing 11, whereby the room in which the heating unit is placed will be efficiently and rapidly warmed.

In the embodiment of the invention illustrated in Figures 5 to 8, the unit is intended to be employed in the same manner as that of Figures 1 to 4. Designated at 33 is a housing of insulating material which is generally cylindrical in form and has a flared supporting base 34. The top wall of the unit comprises a hinged lid 35 having a circular aperture 36 formed thereon and having parallel grill bars 37 secured thereto across the aperture.

Removably secured inside the housing 33 is a cylindrical core member 38 of refractory insulating material such as tile or fire clay formed with annular grooves and secured thereon in said grooves are a plurality of generally C-shaped vapor tubes 39 whose internal construction may be the same as that of the straight vapor tubes 22 employed in the embodiment of Figures 1 to 4. The tubes 39 terminate at end walls 40 and 41, in which are mounted the respective terminals 42 and 43. The terminals 42 at one end of the respective vapor tubes 39 are vertically aligned and are detachably connected to a vertical terminal bar 44 secured in the outer housing 33. The terminals 43 of the respective vapor tubes are similarly vertically aligned and are detachably connected to a second vertical terminal bar 45 secured in outer housing 33 adjacent to and spaced from vertical terminal bar 44. A line wire 46 is connected to terminal bar 44 and a line wire 47 is connected to the terminal bar 45.

A top handle 48 is secured to inner core member 38 to facilitate the removal of said core member from outer housing 33 whenever it is necessary to clean the annular tubes 39. The outer housing 33 is formed with apertures 49 to allow air to circulate around the inner core member 38 past the annular vapor tubes 39. The operation of said vapor tubes is the same as in the embodiment illustrated in Figures 1 to 4.

While certain specific embodiments of a heating stove employing vapor tubes have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An electrical heating element comprising a frame, comprising two spaced refractory plates

and means spacing said plates, conductive plates secured on the facing sides of said refractory plates, a plurality of gaseous electric discharge tubes extending longitudinally between said conductive plates, terminals on opposite ends of said tubes electrically and supportably connecting said tubes to said conductive plates in laterally spaced relation to each other, and refractory cylinders enclosing said tubes arranged to absorb and radiate heat produced by energization of said tubes.

2. An electrical heating element comprising a frame, comprising two spaced refractory plates and means spacing said plates, conductor plates secured on the facing sides of said refractory plates, a plurality of gaseous electric discharge tubes extending longitudinally between said conductive plates, terminals on opposite ends of said tubes electrically and supportably connecting said tubes to said conductive plates in laterally spaced relation to each other, and refractory cylinders enclosing said tubes arranged to absorb and radiate heat produced by energization of said tubes, each of said annular discharge tubes comprising inner, intermediate, and outer refractory tubes, means maintaining said refractory tubes in concentrically spaced relation, said terminals having portions at opposite ends of the discharge tube, said portions being exposed in the interior of the inner refractory tube and in the spaces between the inner tube and the intermediate tube and between the intermediate tube and the outer tube, and ionizable gas filling said spaces.

JOHN I. STEIN.
